US0D1062708S

(12) **United States Design Patent** (10) **Patent No.:** **US D1,062,708 S**
(45) **Date of Patent:** **** Feb. 18, 2025**

(54) **MOBILE PHONE SHELL**

(71) Applicant: **Shenzhen JiaYinMei Electronics Co., Ltd**, Shenzhen (CN)

(72) Inventors: **Zhongyang Nie**, Shenzhen (CN); **Zeyang Nie**, Shenzhen (CN)

(73) Assignee: **Shenzhen JiaYinMei Electronics Co., Ltd**, Shenzhen (CN)

(**) Term: **15 Years**

(21) Appl. No.: **29/887,509**

(22) Filed: **Mar. 22, 2023**

(30) **Foreign Application Priority Data**

Oct. 9, 2022 (CN) 202230662011.1

(51) **LOC (15) Cl.** **03-01**

(52) **U.S. Cl.**

USPC **D14/250**; D14/253

(57) **CLAIM**

The ornamental design for a mobile phone shell, as shown and described.

DESCRIPTION

FIG. 1 is a front perspective view of a mobile phone shell showing our new design;

FIG. 2 is a back perspective view thereof;

FIG. 3 is a front view thereof;

FIG. 4 is a back view thereof;

FIG. 5 is a left side view thereof;

FIG. 6 is a right side view thereof;

FIG. 7 is a top view thereof; and,

FIG. 8 is a bottom view thereof.

The broken lines shown in the drawings depict portions of the mobile phone shell that form no part of the claimed design.

1 Claim, 8 Drawing Sheets
